UNITED STATES PATENT OFFICE.

JOHN T. MONTGOMERY, OF BATTLE CREEK, IOWA.

WALL-PAPER TRIMMER.

SPECIFICATION forming part of Letters Patent No. 554,708, dated February 18, 1896.

Application filed April 11, 1895. Serial No. 545,275. (No model.)

To all whom it may concern:

Be it known that I, JOHN T. MONTGOMERY, a citizen of the United States, residing at Battle Creek, in the county of Ida and State 5 of Iowa, have invented a new and useful Wall-Paper Trimmer, of which the following is a specification.

The object of this invention is to provide a simple, cheap and durable machine into which 10 a roll of paper may be placed and firmly held, and a strip of even width cut from the entire roll with one movement of the operating-lever, especially adapted for trimming the border or waste margin from rolls of wall-paper. 15 My invention consists in the construction, arrangement, and combination of operative parts with a portable frame, as hereinafter set forth, pointed out in my claims, and illustrated in the accompanying drawings, in 20 which—

Figure 1 is a perspective view of the complete device. Fig. 2 is a front elevation of the cutter. Fig. 3 is a transverse sectional view of the knife through the line 3 of Fig. 25 2. Fig. 4 is a front view of a modified form of the device. Fig. 5 is a vertical longitudinal sectional view of the same. Fig. 6 illustrates a modified form of the detachable follower and its connection with the vertically- 30 sliding rod.

Referring to the accompanying drawings, the reference-letter A is used to indicate the frame for supporting the paper, preferably made of cast metal and having a central longitudinal opening, with a rounded bottom of 35 a size and shape to receive a roll of wall-paper. The front A² of the frame is enlarged laterally and arched over the front with an oval opening in alignment with the opening 40 in the frame to receive a roll.

A³ indicates a curved guard inclined upwardly and away from the opening, and A⁴ indicates an arm extended rearwardly and provided with a stop A⁵ to limit the outward 45 movement of the knife, as hereinafter explained.

A⁶ indicates an integral journal on the front A² at one side of the opening therein. B indicates a lever fulcrumed to said journal and 50 having its inner end curved and a handle B² on its outer end. Fixed to the curved portion of the lever is a knife-blade B³ secured

by bolts B⁴, and so shaped as to slide relative to the opening in the front during every portion of its downward movement, thus producing what is known as a "drawing cut" on a roll of paper projected through said opening. It is obvious that when the lever is moved backwardly it will be supported by the stop A⁵, and, furthermore, the knife-blade will be 60 protected by the guard A³.

C indicates a lever fulcrumed to one side of the frame in the lugs C² and extended over the frame at right angles thereto.

C³ indicates a rod pivoted at its outer end 65 and extended downwardly to a foot-treadle C⁴, whereby it may be pulled downwardly by foot-pressure. It is normally held upwardly by means of the contractile coil-spring C⁵.

D indicates a follower having a convex 70 lower surface placed in the opening in the frame with its front edge flush with the front of the frame. D² indicates lugs on its ends admitted into the grooves D³ formed in the frame, thus securely holding the follower in 75 position with its forward face flush with the front and permitting a free vertical movement thereof. This follower is pivotally connected with the lever C by means of the integral arm D⁴.

In the modified form shown in Figs. 4 and 80 5, F indicates a concavo-convex plate designed to be fitted in the bottom of the frame A². This plate may be of any desirable thickness to adapt the machine to receive different-sized rolls. The means for compressing the roll comprises a bar H slidingly mounted in the brace H² and having an enlarged base H³ provided with lugs H⁴ to enter the slots D³ in the frame A² and guide the movement 90 of the bar, and also a dovetailed groove H⁵ to receive a mating projection J from a follower J². J³ indicates two downward projections on the lower surface of the follower. These act in substantially the same manner as the convexed lower surface of the preferred form, the modified form being shown to illustrate the idea that any form by which the central portion of a roll may be compressed will suffice. Followers of different shape may be 95 interchangeably used for paper of different quality and rolls of various degrees of compactness. The bar H is normally elevated by means of a contractile spring K. To press

the bar downwardly a cam K^2 is fulcrumed in the top of the frame A^2 to engage the top of the bar. This cam has a handle K^3 fixed to its upper end.

- 5 In practical use the roll of paper is placed in the frame and its end projected through the front as far as the border on the paper. Then the treadle is operated or the handle pressed downwardly and the follower forced 10 downwardly upon the paper, thus tightly compressing the same. Ordinarily there is a small opening in the center of each roll, and it is practically impossible to cut off a roll accurately until all of the layers of paper are 15 tightly compressed. To thus compress the roll so as to close this central opening it is necessary to have a follower provided with projections on its under surface designed to press a portion only of the roll, and in order 20 to prevent the entire roll from being compressed, and thus causing creases to be formed in the outer layers of the roll, the outer edges of the follower must be on a higher plane than the central portion thereof.
- 25 In order to cut the roll at any particular point designated, it is necessary to first adjust the follower to firmly compress its central portion and hold it against longitudinal movement, and in order to accurately cut on the

line of the border the follower should be adjusted independently of the knife, so that the operator may see the edge of the border. When the paper is thus firmly held the knife is operated, and by a sliding cut the end or margin of the paper is severed. 30

Having thus described my invention, what I claim as new therein, and desire to secure by Letters Patent of the United States therefor, is— 35

1. In a roll-paper cutter the combination 40 of a suitable frame grooved to receive a roll of paper, and a follower mounted in said frame above the groove in the frame to move in a vertical plane and having its lower surface projected downwardly farther at its central portion than at its edges, for the purposes 45 stated.

2. A roll-paper cutter, comprising a suitable frame, the curved knife pivoted thereto, the follower mounted therein, one or more 50 downward projections at or near the central portion of its under face, and independent means for operating the follower, substantially as and for the purposes stated.

JOHN T. MONTGOMERY.
